UNITED STATES PATENT OFFICE.

ROBERT A. BROOKS, OF CHICAGO, ILLINOIS.

DESIGN FOR A DISPLAY CASE FOR USE AS STORE FURNITURE.

Application filed October 13, 1924. Serial No. 11,054. Term of patent 14 years.

To all whom it may concern:

Be it known that I, ROBERT A. BROOKS, a citizen of the United States, residing at 5426 Potomac Avenue, in the city of Chicago, county of Cook, and State of Illinois, have invented a new, original, and ornamental Design for a Display Case for Use as Store Furniture, of which the following is a specification, reference being had to the accompanying drawing, forming part thereof.

Fig. 1, is a side elevation of the display case for use as store furniture embodying my new and original design.

Figs. 2 and 3, are respectively plan and end elevation of same.

I claim:—

The ornamental design for a display case for use as store furniture as shown.

ROBERT A. BROOKS.
